SKI HAT

Erma I. Porter, 4729 South 200 West,
Ogden, Utah 84403

Filed Sept. 19, 1967, Ser. No. 8,650

Term of patent 14 years

Int. Cl. D2—03

U.S. Cl. D2—256

Fig. 1

Fig. 2

Fig. 3

Fig. 4

FIG. 1 is a perspective view of a ski hat showing my new design in a wearing position; and

FIG. 2 is an elevational view thereof with the top in an extended position showing the decorative, continuous detail thereon.

FIG. 3 is a top plan view of the ski hat as shown in FIG. 2; and

FIG. 4 is a bottom plan view thereof.

I claim:

The ornamental design for a ski hat, as shown and described.
